UNITED STATES PATENT OFFICE.

SIDNEY L. CONLAN, OF OAKLAND, AND HERBERT F. PLOUGH, OF INGLEWOOD, CALIFORNIA.

FRUIT-BOX BRACE.

Application filed April 7, 1924. Serial No. 704,603.

To all whom it may concern:

Be it hereby known that we, SIDNEY L. CONLAN and HERBERT F. PLOUGH, citizens of the United States, and residents, respectively, of Oakland, county of Alameda, and State of California, and Inglewood, county of Los Angeles, and State of California, have invented a new and useful Improvement in Fruit-Box Braces, of which the following is specification.

This invention relates more particularly to the transportation of green fruit.

An object of our invention is the provision of means for securely bracing fruit carriers in refrigerator cars to prevent same from shifting and becoming damaged in shipping.

A second object is the elimination of waste lumber entailed every time the wooden braces, now in common use, are discarded after the car is unloaded.

A third object is the saving of a large portion of the time required to install the usual wooden braces.

A fourth object is the provision of an exceedingly simple and efficient means for bracing fruit boxes in cars, which means will be capable of greater range than is possible in the device described in our application, Serial No. 683,430, filed December 29, 1923, over which this device is an improvement.

A fifth object is to reduce the number of parts required, and to prevent these parts from becoming separated during storage.

We accomplish these results in the manner set forth in the following specification and illustrated in the accompanying drawing, in which:

Figure 1 is a side elevation of the device extended to its limit between two stacks of fruit boxes. Figure 2 is a section through one of the expanding jacks showing the braces in the position of utmost contraction. Figure 3 is a section along the line 3—3 in Figure 1.

It will be understood that this device is an improvement over the form described in the application above mention. In this case we prefer to dispense with one of the jacks and use slightly heavier channels of the type known as car building channels, which are best adapted for the purpose, as these channels have stronger side members than have the standard channels, and

it is in this direction that strength is desired.

Another object in employing two jacks instead of three is to facilitate the operation of the jacks themselves; although it must be understood that three jacks can be employed if so desired.

It will be observed that by this construction all of the parts of the device are held together and can only be separated by the operation of the jacks themselves.

Similar numbers of reference refer to the same parts throughout the several views.

Referring in detail to the drawing, we have illustrated the fruit boxes 10 which are piled from the car ends toward the center door and are separated vertically by the spacer bars 11, which extend to the sides of the refrigerator car, as is the common practice.

The space left between the boxes in the doorway of the cars varies with the kind of boxes being packed, and other factors, from fourteen inches up to three feet or more.

A brace, as shown in Figure 1, is placed between each row of boxes, and this brace consists of the box-engaging channel irons 12 and 13 between which are placed the jacks in which this improvement resides.

To the channel iron 12 is loosely hinged, by means of the pin 14, the hollow left-hand screw 15. One of the corners 16 of the screw 15 is rounded and the other corner 17 is square and acts as a stop against the channel, although in some cases we prefer to omit the square corner altogether.

On the screw 15 is placed an internally threaded sleeve 18 whose end 19 has a reduced diameter and is also threaded to receive the smaller right-hand screw 20 which is hinged to the member 13 by the pin 21. The end 19 is provided with a hexagonal exterior 22 to receive an operating wrench (not shown). The two jacks are exactly alike, and as many sets of the device as shown in Figure 1 are required as there are rows of boxes in the width of the car.

Holes 23 may be provided in the channel irons 12 and 13 for nailing into the boxes 10 in order to prevent the braces from falling after unusually rough handling of the car.

The operation of our device is as follows: After the boxes 10 are piled into the car, as

suggested, leaving only a short space, sometimes as little as fourteen inches, in the doorway of the car, the braces are contracted sufficiently to be placed in the breach and 5 expanded by operating the jacks with a wrench. If desired, enough nails can be driven into the holes 23 to insure the braces remaining in an upright position under all circumstances. That is all there is to it.

10 When the cars are empty, the braces are stored away in overhead hangers, as may be found most convenient.

By this construction we are enabled to secure a large working range for the brace, 15 which of course is very desirable. While it would be possible to use a ratchet jack in place of the screw, this style of expanding device is not deemed practicable owing to the limited space in which the operator is 20 often called upon to work. Furthermore, greater thrust can be secured by the rotary motion of the screws than by the ratcheting action of other devices.

While we have indicated our jacks as attached to the channel irons by hinges this is 25 not actually required, although it is considered to be the best form since it holds the device intact and no strain is placed on

the hinges, since the pins are sufficiently loose to transfer the load from the screws 30 directly to the channel irons themselves. In some instances it might be desired to employ a T iron instead of a channel. This can be done without departing from the spirit of our invention.

35

We claim:

A fruit brace having, in combination, a pair of upright channel members adapted to be nailed between the boxes of fruit stacked in the ends of a car, said members having 40 their channel sides facing each other; pairs of tubular members between said channels, said tubes having a large diameter internal thread almost their entire length and a small diameter internal thread at one end thereof; 45 screws hinged to one of said channels threading into the smaller threaded openings of said tubular members; a pair of externally threaded tubes hinged to the opposite channel and screwing into the larger openings 50 in said first mentioned tubular member, said last mentioned tubular member having an opening large enough to receive said screw member.
